(57) **CLAIM**

The ornamental design for a plant growing light, as shown and described.

DESCRIPTION

FIG. 1 is a front perspective view of a plant growing light showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged front perspective view of the light part of the plant growing light, shown in the selected portion in FIG. 1; and,

FIG. 10 is an enlarged rear perspective view thereof, shown in the selected portion in FIG. 2.

The broken lines shown in the figures are for the purpose of illustrating portions of the plant growing light, which form no parts of the claimed design.
